SUCTION CUP SOAP DISH

Paul F. Simpson, Oakville, Conn., assignor to The
Autoyre Company, Oakville, Conn., a corpora-
tion of Connecticut

Application April 3, 1950, Serial No. 8,953

Term of patent 14 years

(Cl. D4—3)

To all whom it may concern:

Be it known that I, Paul F. Simpson, a citizen of the United States, residing in Oakville, State of Connecticut, county of Litchfield, have invented a new, original, and ornamental Design for Suction Cup Soap Dish, of which the following is a specification, reference being had to the accompanying drawing, forming a part thereof.

In the drawing, illustrating by new design:

Fig. 1 is a top plan view of a suction cup soap dish showing my new design;

Fig. 2 is an end elevational view; and

Fig. 3 is a rear elevational view thereof.

The dominant features of my new design for suction cup soap dish have been illustrated in the drawing in full lines and is particularly characterized by the configuration and disposition of the substantially rectangular brace member centrally located at the rear thereof.

What is claimed is:
The ornamental design for a suction cup soap dish, substantially as shown and described.

PAUL F. SIMPSON.
